UNITED STATES PATENT OFFICE.

PHILLIP OSWALD, OF SYRACUSE, NEW YORK.

DESIGN FOR A BUCKLE-FRAME.

SPECIFICATION forming part of Design No. 33,686, dated December 11, 1900.

Application filed November 2, 1899. Serial No. 735,645. Term of patent 14 years.

To all whom it may concern:

Be it known that I, PHILLIP OSWALD, of Syracuse, in the county of Onondaga and State of New York, have invented and produced a new and original Design for a Buckle-Frame, of which the following, taken in connection with the accompanying drawings, is a specification.

Figure 1 is a top plan view of a buckle-frame embodying my design. Fig. 2 is a longitudinal sectional view taken on line X X, Fig. 1. Fig. 3 is an isometric view of said buckle-frame.

The leading feature of my design consists of a buckle-frame which when viewed in top plan presents substantially the appearance of a parallelogram, having its intermediate portion subdivided by cross-bars arranged substantially parallel with its end bars, one of said bars being depressed beneath the other, and when viewed in side elevation presents substantially the appearance of an arc, having midway between its ends depending extensions uniting the ends of the depressed

cross-bars to the contiguous portions of the 25 buckle-frame.

1 1 and 2 4 are the side and end bars of the buckle-frame.

3 5 are the cross-bars, arranged parallel with the end bars 2 4, the cross-bar 5 being depressed beneath the cross-bar 3, and 6 6 are depending extensions arranged midway between the ends of the buckle-frame and uniting the ends of the cross-bar 5 to the contiguous portions of the side bars 1 1. 35

A buckle-frame embodying my design presents a graceful, pleasing, and characteristic appearance.

What I claim is—

The design for a buckle-frame, substantially as herein shown and described. 40

In testimony whereof I have hereunto set my hand in the presence of two attesting witnesses.

PHILLIP OSWALD.
